UNITED STATES PATENT OFFICE.

ULYSSE N. TREMBLEY, OF LAWRENCE, MASSACHUSETTS.

SHUTTLE.

1,267,824.

Specification of Letters Patent.

Patented May 28, 1918.

Application filed June 25, 1917. Serial No. 176,908.

To all whom it may concern:

Be it known that I, ULYSSE N. TREMBLEY, a citizen of Canada, residing at Lawrence, in the county of Essex and State of Massachusetts, have invented certain new and useful Improvements in Shuttles, of which the following is a specification.

This invention relates to shuttles for looms and particularly to the type known as hand threading shuttles.

In the old fashioned suction shuttle, a round porcelain ring was used as a shuttle eye, and this eye wore a long time. With modern types of hand threading or self-threading shuttles, it has not been possible to use an endless ring, and other porcelain devices, which have been used, have been expensive and difficult to make, while metal parts or parts of other material wear out so rapidly from the friction of the yarn that great replacement expense is entailed, and there is also more likelihood of the yarn wearing a groove and breaking.

My invention is applicable to that class of hand threading shuttles which have a bobbin recess with which connects a hole or passage to receive a shuttle eye or plug usually of substantially cylindrical shape and of metal. My invention consists principally in so making and positioning such a plug that the yarn in traveling from the bobbin out through the plug or eye, after once being threaded, will come in contact with only smooth, round surfaces of porcelain or similar material.

It is also arranged that the plug can readily be removed in order to replace broken or otherwise damaged parts.

In the drawings, Figure 1 is a plan view of what I will call the front or forward end of a shuttle, parts being broken away to show the location of my plug. Fig. 2 is an elevation from the right of Fig. 1. Fig. 3 is a plan view of my plug removed from the shuttle, and also shows the machine screw which I prefer to use for convenience in removing it from the shuttle. Fig. 4 is an elevation of my plug as from the back. Fig. 5 is a view as from the front, and Fig. 6 is a view as from the bottom. Fig. 7 is an enlarged elevation of the outlet of the plug or shuttle eye. Fig. 8 is an enlarged section from the right on line 8-8 of Fig. 3. Fig. 9 is a plan view of a shuttle with a modified form of my device in which the delivery slot passes vertically up and through the outlet

of the plug at the top instead of at the bottom.

Fig. 10 is a perspective view of a plug which is not cylindrical.

A represents a shuttle which has a bobbin recess B to receive the bobbin C from which the filling or yarn F is unwound. K represents the usual longitudinal groove which runs along that side of the shuttle where is the outlet of the shuttle eye.

As shown, the bobbin recess B extends toward the front or forward in the form of a neck 19 which is, however, part of the bobbin recess. Transversely of the shuttle from the side opposite the yarn groove K, I bore a hole 10 which is preferably substantially cylindrical. I prefer to leave a small amount of wood at 12 and 14 between the end of hole 10 and the inner edges of groove K to serve as a stop for the plug which is to be inserted in hole 10. This hole 10 is so bored that its end cuts the curved wall of yarn groove K about midway thus leaving some wood 12 and 14 to serve as a stop. I also prefer to cut a supplementary groove or eye 13 which extends from each side of the plug.

Extending forward from the part 19 of the bobbin recess, I cut a threading slot 17 which extends forwardly and downward out toward the side of the shuttle where is the outlet of the shuttle eye, and thence backward substantially parallel with the top of the shuttle at 18 until this threading slot 17 enters the hole 10 whereby the yarn can be carried forward and then back into such hole in a well known manner.

H is a plug or conductor which is preferably substantially cylindrical, has a yarn passage 25 which extends longitudinally of the plug and laterally of the shuttle out through one end which I will call the outlet of the plug. Into this passage 25 there is cut from the top a recess 30 in such a position that it registers with the inside end of threading slot 17. From this recess extends a plug slot 31 to a point where it connects with a vertical outlet slot 33. Slot 31 is shown as extending diagonally downward and outward and recess 30 may be considered part of it.

Plug H is trimmed down at 72 so as to leave room for the yarn to pass between it and the inside of hole 10 as it slips through the slots.

This side 73 of the outlet end of the plug

is also slightly shorter than the other end 74 to allow the yarn to pass into slot 33.

It is evident that instead of trimming down the plug at 72, and instead of making the side 73 of the outlet end somewhat shorter than the other side, the wood of the shuttle could be cut away to permit the yarn to pass, but in practice, it is easier to shape the plug than it is to shape the wood.

10. The portion of wood 14 which is left at the bottom under the cut away part 13 at the end of hole 10, preferably projects upward above the lower part of side 73 and helps to prevent the yarn from unthreading 15 by slipping down from passage 25 back through vertical outlet slot 33 and into plug slot 31.

20. To serve as guides or bearings for the yarn as it passes from the bobbin out through the shuttle eye device, I use porcelain pins each of which is driven through a pin hole in one part of the shell, and into another hole in a part of the shell which is nearly opposite, as shown clearly in Fig. 8. 25. The pins 41 and 40 are positioned close to the outlet of plug H and driven from the top through parallel pin holes 51 and 50, which preferably terminate in dead ends 52 and 53 as they extend into but not 30 through the shell.

I prefer to bore small releasing holes 61 and 60 into the dead ends 52 and 53 of the pin holes, whereby the pins 41 and 40 may be readily driven out by inserting a small 35 rod and tapping it. There is less danger of the yarn catching as it passes over the small releasing holes than there would be if it passed over the end of a pin such as 40 and 41, which had not been carefully 40 smoothed. As shown in Fig. 8, pins 40 and 41 need not accurately fit pin holes 50 and 51 and their ends need not be smooth but may be left rough as they are protected by the dead ends 52 and 53 and at their other 45 ends by the wood on the inside of the plug hole 10. My porcelain pins need not be accurately made and need not fit into the pin holes closely, although I prefer to drive them in, as when the plug is in place in 50 the plug hole 10, the end or ends of the pin holes 50 and 51 are closed by the material in which plug hole 10 is made, so that the pins cannot get out.

A passage is therefor left between pins 41 and 40 into the tubular inside part 25 of the plug H, and the yarn can enter between these pins as it passes down through slot 31, trimmed away part 73, around end 73 and through slot 33 into yarn passage 25 where 60 it remains.

The pin 42 is placed at such a point that it will protrude beyond the cut away part 34 of recess 30 so that it will guide the yarn F from the bobbin in such a manner that it 65 will touch no other part and allow it to turn

at substantially right angles to pass between the pins 40 and 41 near the outlet of the plug.

Pin 42 is preferably driven up through a hole 45 in the bottom of the tubular shell 70 of plug H and into a dead end which enters but does not pass through the other or top side of the shell. A small releasing hole 44 enters this dead end whereby the pin can be readily driven out and its end does not 75 come in contact with the yarn in the threading process.

The plug H may be driven in so as to not quiet touch the wood left at 12 and 14, thus leaving space for the yarn to pass, in which 80 case, the end 73 may be as long as 74, but I prefer to drive it in so that its long end 74 will rest against the wood at 12 and 14 as shown by the dotted line in Fig. 6. In either case, I prefer to hold it in position 85 by means of a pin 16 which is driven down through the wood of the shuttle and into a hole 15 in the plug. In this way, the yarn can pass from recess 30 through threading slots 17, 18, and plug slots 31 and 33 down 90 along the trimmed off portion 72 and between the shorter outlet end 73 of the plug, and the end of large hole 10 slipping up in between the pins 40 and 41, and out through the eye groove or opening 13. 95

I find it convenient at 20 to thread the end of plug H which is opposite the outlet, to receive the threaded shank of a screw 21 whereby this end of the plug can be sunk out of sight and still the plug can readily 100 be removed after removing the pin 16 through the medium of screw 21.

The outlet end of plug H is recessed at 70 and 71 to correspond with the curve of groove 13 to allow the pins 40 and 41 to direct the yarn clear of any metal part. 105

In Fig. 9, I show a slight modification in which the recess 30 of plug H and the threading slots 17 and 18 in the wood are the same but the plug slot 82 and outlet slot 110 83 extend toward the top instead of toward the bottom so that outlet slot 83 extends out vertically between the pins 40 and 41 at the top instead of the bottom. The top end 85 is trimmed off to allow the yarn to pass. 115

In Fig. 10 I show a square plug T which is arranged for a shuttle with an eye or yarn outlet at the left instead of at the right. This has a recess 90 which corresponds with 30, and plug slots 91 and 92 which correspond with 31 and 33, while the pins 40 and 41 are the same, as is also the guide pin 93 which corresponds with 42.

I prefer to make the exterior pins 40 and 41, and the interior pin 42 of the same size 125 and interchangeable, and it is not necessary that they should be of any exact length, as an examination of pin 41 in Fig. 8 will indicate. It is merely necessary that they should not project above the surface of the plug so 130

as to interfere with its being pushed into the plug hole in the wood.

Each pin may fit loosely in its pin hole and its ends may be unfinished, as it is put in place before the plug is inserted in the plug hole 10 and when the plug is in place the pins cannot escape from their holes because there is a dead end, such as 52 or 53, at one end and the inside surface of the plug hole, 10 such as 10, prevents their escape in the other direction.

It is clear that many other forms of threading slots might be used, and it is clear that in place of the plug, I might use any 15 form of removable member with a pin or pins held at a point or points where it or they will serve as a bearing for the yarn in a pin hole and against the wood of the shuttle.

20 Where two parallel pins are used, they must be so located that there is a yarn passage and a yarn slot between them.

I so position the open ends of my pin holes that they will come close to the inside 25 surface of the plug hole and will, therefore, be closed so that the pin cannot get displaced or shake out. In this way, where it is necessary for the yarn to pass by the end of the pin, there is little, if anything, for it to catch 30 on except the releasing hole which may be very small.

As shown in Fig. 9, instead of leaving any wood at 12 and 14 and instead of making 35 one end of the plug, such as 73, shorter than 74, I can bore the plug hole clean through the shuttle, as shown at 84, and depend upon holding it in position by means such as pin 16.

I claim:

40 1. The combination in a loom shuttle having a bobbin recess, a lateral plug hole which enters the bobbin recess and extends through the side of the shuttle, and a diagonal threading slot which extends from the front 45 end at the top of the recess, forward and downward therefrom, thence back through the side substantially parallel with the top and into said hole, of a plug which fits into said hole and has a yarn passage with an 50 outlet through the side of the shuttle, a recess which passes from the top into the yarn 55 passage and which registers with the inside end of the threading slot, a plug slot which runs from the recess diagonally and thence 55 vertically out through the plug outlet, and a cut away portion of the plug which extends from the threading slot to the plug slot, and exterior porcelain pins fixed therein on each side of the plug slot near the outlet of the 60 plug.

2. The combination in a loom shuttle having a bobbin recess and a lateral plug hole through its side which enters the front end of the bobbin recess and a threading slot 65 which extends from the bobbin recess into

such lateral hole, of a plug which fits into such hole and has a yarn passage which extends out through the side of the shuttle, a plug slot which near its inlet registers with the threading slot and enters the yarn passage 70 and extends out vertically through the end of the plug, together with exterior pins fixed therein on each side of the last named slot near the outlet of the plug.

3. The combination in a loom shuttle having a bobbin recess and a lateral plug hole through its side which enters the front end of the bobbin recess and a threading slot which extends from the bobbin recess into 80 such lateral hole, of a plug which fits into such hole and has a yarn passage which extends out through the side of the shuttle, a plug slot which near its inlet registers with the threading slot and enters the yarn passage 85 and extends out vertically through the end of the plug, and parallel vertical pin holes which pass into the plug and terminate in dead ends on each side of and near the outlet of the plug slot, and pins driven into 90 said pin holes.

4. The combination in a loom shuttle having a bobbin recess and a lateral plug hole through its side which enters the front end of the bobbin recess and a threading slot which extends from the bobbin recess into 95 such lateral hole, of a plug which fits into such hole and has a yarn passage which extends out through the side of the shuttle, a recess which passes from the top into the 100 yarn passage and which registers with the inside end of the threading slot, a plug slot which runs from the recess diagonally and thence vertically through the outside end of the plug, parallel vertical pin holes which pass into the plug and terminate in dead 105 ends on each side of and near the outlet of the plug slot, and an interior pin hole which extends into the plug through the yarn passage and terminates in a dead end in position to be partly inside the plug recess, and 110 porcelain pins driven into said pin holes.

5. The combination in a loom shuttle having a bobbin recess, a yarn groove, and a lateral plug hole through one side which passes through the front end of the bobbin recess 115 and into but not through the yarn groove and a threading slot which extends from the bobbin recess into such lateral hole, of a plug which fits into such hole and has a yarn passage which extends from the bobbin recess 120 into the yarn groove, a recess which passes from the top into the yarn passage and which registers with the inside end of the threading slot, a plug slot which runs from the recess diagonally and thence vertically 125 into the yarn passage and through the outside end of the plug, a cut away portion between the plug slot and the yarn passage, parallel vertical pin holes which pass into the plug and terminate in dead ends on each 130

side of and near the outlet of the plug slot, and an interior pin hole which extends into the plug through the yarn passage and terminates in a dead end in position to be partly inside the plug recess, and porcelain pins driven into said pin holes.

6. The combination in a loom shuttle having a bobbin recess, a yarn groove, and a lateral plug hole through one side which passes through the front end of the bobbin recess and into but not through the yarn groove and a threading slot which extends from the bobbin recess into such lateral hole, of a plug which fits into such hole and has a yarn passage which extends from the bobbin recess into the yarn groove, a recess which passes from the top into the yarn passage and which registers with the inside end of the threading slot, a plug slot which runs from the recess diagonally and thence vertically into the yarn passage and through the outside end of the plug, a cut away portion between the plug slot and the yarn passage, parallel vertical pin holes which pass into the plug and terminate in dead ends on each side of and near the outlet of the plug slot, and an interior pin hole which extends into the plug through the yarn passage and terminates in a dead end in position to be partly inside the plug recess, the outside end of the plug being cut away to register with the yarn groove and to expose the outside pin holes and the recess being cut away to expose the inside pin hole, and porcelain pins driven into said pin holes.

7. A removable member for loom shuttles which has a yarn passage which extends out through one end, a recess which passes from the top into the yarn passage, a slot which runs from the recess diagonally and thence vertically through the outside end of the yarn passage, parallel vertical pin holes which pass into the removable member and terminate in dead ends on each side of and near the outlet of the yarn passage, and an interior pin hole which extends into the removable member through the yarn passage and terminates in a dead end in position to be partly inside the recess, and porcelain pins driven into said pin holes.

8. A plug for loom shuttles having a yarn passage with an outlet and a slot which extends therefrom and porcelain pins therein on each side of such slot near the outlet of the plug.

9. A plug for loom shuttles having a recess, a yarn passage with an outlet and a slot which extends therefrom vertically and thence to the recess, and porcelain pins therein on each side of such slot near the outlet of the plug.

10. A plug for loom shuttles having a recess, a yarn passage with an outlet and a slot which extends therefrom vertically and thence to the recess, and removable exterior

porcelain pins therein on each side of such slot near the outlet of the plug, together with a removable interior porcelain pin which projects into the recess.

11. The combination in a loom shuttle having a bobbin recess and a lateral plug hole through its side which enters the front end of the bobbin recess and a threading slot which extends from the bobbin recess into such lateral hole, of a plug which fits into such hole and has a yarn passage which extends out through the side of the shuttle, a plug slot which near its inlet registers with the threading slot and enters the yarn passage and extends out vertically through the end of the plug, parallel vertical pin holes which pass into the plug and terminate in dead ends on each side of and near the outlet of the plug slot, and releasing holes which enter the dead ends of the pin holes, the outside end of the plug being cut away to register with the yarn groove and to expose the outside pin holes, with pins driven into said pin holes.

12. The combination in a loom shuttle having a bobbin recess and a lateral plug hole through its side which enters the front end of the bobbin recess and a threading slot which extends from the bobbin recess into such lateral hole, of a plug which fits into such hole and has a yarn passage which extends out through the side of the shuttle, a plug slot which near its inlet registers with the threading slot and enters the yarn passage and extends out vertically through the end of the plug, and parallel vertical pin holes which pass into the plug and terminate in dead ends on each side of and near the outlet of the plug slot, their open ends being closed by the inside surface of the plug hole, with pins driven into said pin holes.

13. The combination in a loom shuttle having a yarn groove, a bobbin recess and a lateral plug hole through its side which enters the front end of the bobbin recess and a threading slot which extends from the bobbin recess into such lateral hole, of a plug which fits into such hole and has a yarn passage which extends out through the side of the shuttle, a plug slot which near its inlet registers with the threading slot and enters the yarn passage and extends out vertically through the end of the plug, parallel vertical pin holes on each side of and near the outlet of the plug slot, the outside end of the plug being cut away to register with the yarn groove and to expose the outside pin holes, with pins in said pin holes.

14. The combination in a loom shuttle having a bobbin recess and a lateral plug hole through its side which enters the front end of the bobbin recess and a threading slot which extends from the bobbin recess into such lateral hole, of a plug which fits into such hole and has a yarn passage which ex-

tends out through the side of the shuttle, a plug slot which near its inlet registers with the threading slot and enters the yarn passage and extends out vertically through the end of the plug, and pins in such plug so located on each side of the outlet of the plug slot as to direct the yarn clear of any other part of the plug.

15. The combination in a loom shuttle
10 having a yarn groove, a bobbin recess and a lateral plug hole through its side which enters the front end of the bobbin recess and extends into the yarn groove and a threading slot which extends from the bobbin recess into such lateral hole, of a plug which

fits into such hole and has a yarn passage which extends out through the side of the shuttle, a plug slot which near its inlet registers with the threading slot and enters the yarn passage and extends out vertically 20 through the end of the plug, the plug being cut away to allow the yarn to pass from the threading slot to and into the plug slot and its outside end being cut away to register with the yarn groove, and pins in such plug 25 located on each side of the outlet of the plug slot.

In testimony whereof I have affixed my signature.

ULYSSE N. TREMBLEY.
